UNITED STATES PATENT OFFICE.

FRANK CHATEAUNEUF, OF HAVERHILL, MASSACHUSETTS.

TACK-PULLING MACHINE.

No. 827,962.

Specification of Letters Patent.

Patented Aug. 7, 1906.

Application filed July 3, 1905. Serial No. 268,071.

To all whom it may concern:

Be it known that I, FRANK CHATEAUNEUF, of Haverhill, county of Essex, State of Massachusetts, have invented an Improvement in Tack-Pulling Machines, of which the following description, in connection with the accompanying drawings, is a specification, like characters on the drawings representing like parts.

10 This invention relates to that class of machines which are designed to pull out lasting-tacks from shoes.

My invention has for its special object to improve the means for removing the tacks in a machine of the above character, so that they will be removed under difficult conditions and will be effectively freed from the work, so that they will not be carried into engagement with the knives either before or

20 after they have been removed.

I accomplish these objects by the means shown in the accompanying drawings, in which—

Figure 1 is a side elevation of the machine 25 provided with my invention. Fig. 2 is a plan view thereof. Fig. 3 is a detail view of the knife-operating mechanism. Figs. 4 and 5 are sectional views on the line 3 4 of Fig. 1, Fig. 4 showing the parts in the retracted position of Fig. 1 and Fig. 5 showing them in an advanced position. Fig. 6 is a side elevation of the main working parts of the machine, showing them in the position of Fig. 5.

The head *a* of the machine is provided with 35 a forwardly-extending arm *a'*, and a suitably-driven main shaft *b* is journaled in said head. A horizontally-disposed knife *c* is secured to the front end of a holder *c'*, which is reciprocally mounted in the front end of the arm *a'*, 40 at the lower side thereof, a connecting-rod *c* being pivoted thereto and connected to an eccentric-strap *c*, mounted on an eccentric *c*, secured to the main shaft *b*. A horizontally-disposed bracket *d* is secured to the arm *a'*, and a vertically-disposed bracket *d'* is secured to the front end of the arm *d*, to the lower end of which is secured a horizontally-disposed knife *e*, provided with a cutting edge positioned to coöperate with the cutting 45 edge of the knife *c*, so that as the knife *c* is reciprocated they will act as a shear, the knife *c* being beveled on the upper side and the knife *e* on the lower side and the knife *e* passing close to the upper side of the knife *c*. 50 Both cutting edges extend divergently, as shown. In trimming the seam the shoe is

fed from right to left in a manner which will be obvious.

A guard *f* is formed on the lower end of a lever *f'*, which is pivoted at *f* on the bracket *d'*. The upper end of lever *f'* is connected by a link *f* to the upper end of a vertical arm *f*, mounted on the rear end of holder *c'*. The guard *f* is provided with a vertical work-engaging face extending obliquely to the edge 65 of knife *e*, the lower edge of said face swinging in the path as closely as practicable to the path of knife *c*. With this arrangement the guard will be swung rearwardly as the knife is moved forwardly, and the parts 70 are so timed that the face of the guard will always be closely adjacent the cutting-point of the knives and will thus act as a support for the projecting portion of the seam which is to be trimmed off, so that such portion will 75 be held vertically while it is being cut, and the danger of the moving knife riding over the work when it is dull instead of cutting it will be to a great extent eliminated. Moreover, 80 after a portion of the guard passes the cutting-point it will continue to move rearwardly and will push back the strip which is removed out of the way of the operator, as indicated in Fig. 4, so that the strip will not interfere with his work.

A pair of guideways *a* are provided in the right-hand side of the arm *a'*, and a carrier *g* is reciprocally mounted between said guideways, suitable means for reciprocating said carrier being provided, as the connecting-rod *h*, eccentric-strap *h'*, and eccentric *h*, mounted on the main shaft *b*. A downwardly-extending bracket *g'* is secured to the carrier *g*, and a holder *i* is pivotally connected thereto by means of a pivot-bolt *i'*. A pair of tack-pulling bars *j* and *k* are reciprocally mounted side by side in the holder *i* and at the right of the knives *c* and *e* and adjacent thereto, the front ends of said bars being provided with tack-claws *j'* and *k'*. Springs *m* and *n* are each 95 connected to the holder *i* at their front ends and at their rear ends, respectively, to pins *j* and *k*, said springs normally holding said pins against the holder, which limit their forward movement in the latter, as indicated in Fig. 3. An arm *o* is connected to the under side of the holder *i*, and a link *p* is connected at one end to the rear end of said arm and at the other to the front end of a cam-lever *q*, which is 100 pivoted at *q'* to the arm *a'* and is provided with a roll *q*, which rides on a cam *q* on the 105

main shaft, a spring *s* being connected to said cam-lever *q* to hold said roll in contact with said cam.

The operation of the tack-pulling devices 5 is as follows: The shaft being rotated, the carrier *g* is caused to reciprocate horizontally, carrying the claw-bars *j* and *k* in the same direction. The cams *c*⁴ and *h*² are set practically coincident, so that knife *c* and bars *j* 10 and *k* advance together. At the same time the cam-lever *q* causes the holder *i*, and therefore the claw-bars, to be tipped in a vertical plane, thus raising and lowering the front ends of the latter. The cams *g*³ and *h*² are so 15 timed and formed that the claw-bars will be advanced when their front ends are in their lowest position and will be swung upwardly at the end of their forward movement and then withdrawn in the raised position (see 20 dotted position of Fig. 6) and then lowered again until they are returned to the initial position of Fig. 1. As the work is fed from right to left to trim off the seam the lasting-tacks will be engaged by the bars *j* *k* before 25 the portions of the shoe in which they are located reach the knives. As a tack is engaged by the claw in one of the horizontally-moving bars *j* or *k* the forward movement of the bar will be arrested, and then as the claw 30 end of the bar is swung upwardly the tack will be pulled out of the shoe. The extent of the forward movement of the bars is such that their front ends will be carried beyond the point in which the seam is usually held, 35 so that at the time the tack is pulled out the bar which engages it will be under more or less tension, and as the bar is free to move forward to its fullest extent as soon as the tack is withdrawn and the bar has been carried 40 above the seam the tack which has been withdrawn by the bar and is still in engagement therewith will be thrown forward over the seam by the bar as the bar is shot forward by the action of the spring. The tack is thus 45 usually thrown entirely free of the shoe, so that the possibility that a tack which has been removed will lodge on the seam and will be engaged by the knives is exceedingly remote. As the bars may yield independ- 50 ently, each may be moved into engagement with tacks set at different distances from the edge of the shoe on the same forward move-

ment of the bars. The simultaneous withdrawal of two tacks driven close together at different distances from the edge of the shoe 55 is thus accomplished.

In lasting the heel and toe of a shoe the upper is necessarily plaited, and if a single bar of the width of the two bars *j* and *k* were employed the forward movement thereof would 60 frequently be intercepted by one of the plaits, so that it could not advance sufficiently to engage the tack; but with my device if one of the bars is intercepted by a plait the other bar is still free to advance and pass between 65 the plait which has engaged the one bar and the adjacent plait, so that it may engage and remove a tack.

Having thus described my invention, what I claim as new, and desire to secure by Letters Patent, is—

1. A tack-pulling device comprising a plurality of independently and rearwardly yielding tack-engaging devices, and means for moving said engaging devices forwardly simultaneously, substantially as described. 75

2. A tack-pulling device comprising a holder, a plurality of forwardly-spring-pressed tack-engaging devices reciprocally mounted in said holder, and means for moving said holder forwardly, substantially as described. 80

3. A tack-pulling device comprising a carrier, a holder pivotally connected thereto, means for simultaneously reciprocating said carrier horizontally and swinging said holder vertically, and a forwardly-spring-pressed tack-claw reciprocally mounted in said holder, 85 substantially as described.

4. A tack-pulling device comprising a holder, a plurality of horizontally-disposed bars, each having a tack-claw in its forward end and reciprocally mounted in said holder, springs for pressing said bars forwardly, and means for moving said holder to carry the 95 forward ends of said bars forwardly and then vertically, substantially as described.

In testimony whereof I have signed my name to this specification in the presence of two subscribing witnesses.

FRANK CHATEAUNEUF.
